UNITED STATES PATENT OFFICE.

LIONEL TREMBLAY, OF MONTREAL, QUEBEC, CANADA, ASSIGNOR OF ONE-HALF TO
AUGUSTIN ROUSSELLE, OF MONTREAL, QUEBEC, CANADA.

ENGINE-BASE OIL FEEDER.

Application filed May 11, 1923. Serial No. 638,413.

To all whom it may concern:

Be it known that I, LIONEL TREMBLAY, a subject of the King of Great Britain, and residing at 549^a Grand Trunk Street, 5 in the city of Montreal, in the Province of Quebec, in the Dominion of Canada, have invented a new and useful Engine-Base Oil Feeder, of which the following is the specification.

10 The invention relates to an engine base oil feeder, as described in the present specification and shown in the accompanying drawings that form part of the same.

15 The invention consists essentially of the novel features pointed out broadly and specifically in the claims for novelty following a description containing an explanation in detail of an acceptable form of the invention.

20 The objects of the invention are to insure a constant and even supply of oil in the base of gasoline engines by automatic feeding mechanism; to account for the different positions of the engine base and feed 25 walls due to hills in the line of travel of a motor car; and generally to provide an efficient and reliable oil feed device.

20 In the drawings Figure 1 is a bottom view of an engine base showing the plan of the 30 feed wells and connections.

Figure 2 is a side elevation of an engine base showing the oil feed device applied thereto.

35 Figure 3 is a plan view looking down on one feed well.

Figure 4 is a plan view looking down on the other feed well.

Figure 5 is a vertical sectional view of one feed well.

40 Figure 6 is a vertical sectional view of the other feed well.

Figure 7 is a perspective detail of the float.

45 Figure 8 is a sectional detail of the cover of the feed well connected to the tank.

Like numerals of reference indicate corresponding parts in the various figures.

Referring to the drawings, the engine base 1 is formed with the central threaded 50 inlet 2 through the bottom thereof into which is screwed the three way union 3.

The pipes 4 and 5 lead upwardly from the union 3 in a slanting direction and are inserted in the feed wells 6 and 7 in the 55 bottom outlets 8 and 9.

The feed well 6 is secured to the base 1 at the front part thereof by bolts 10 through the brackets 11 and 12 extending above the feed well and offset at their upper ends.

The feed well 7 is secured to the base 1 60 at the rear side by means of the bolts 13 through the brackets 14 and 15 offset at their upper ends above the well.

The central guide post 16 extends upwardly from the bottom of the feed well 65 6 and the central guide post 17 extends upwardly from the bottom of the feed well 7, a float 18 being slidably mounted on the post 16 and a float 19 being slidably mounted on the post 17. 70

In the feed well 6 the float stem 20 is screwed into the float 18 in the post orifice 21 and is pivotally joined to the valve stem 22.

The float stem 24 is screwed into the float 75 19 in the post orifice 25 and is pivotally joined to the valve stem 26.

The cover 27 of the feed well 6 is formed with the central threaded vent orifice 28 into which the bent pipe 29 is screwed and held 80 by the nuts 30.

The boss 31 projects from the inner side of the cover 27 and is bored to form a cylindrical chamber for the cylinder valve 32, which is closed at the ends and has the 85 inlet port 33 adapted to register with the inlet port 34 in the chamber wall, and the outlet port 35 adapted to register with the outlet port 36 in the chamber wall leading to the interior of the feed well 6. The inlet port 34 forms a passage through the boss 31 and cover 27 and is threaded towards the outer end and the nipple 37 is screwed into the passage for the purpose of connecting the valve 32 by means of the pipe 90 38 with the feed well 7.

The feed 7 is closed in by the cover 39 having the central threaded vent orifice 40 and carrying the curved vent pipe 41 100 screwed into said orifice 40.

The boss 42 projects inwardly from the cover 7 and is bored to form a valve chamber for the cylinder valve 43, the latter having the inlet port 44 adapted to register with the inlet port and passage 45 through the 105 boss 42 and cover 39 and the outlet port 46 adapted to register with the port and passage 47 through the boss 42 and cover 39 and parallel with the port and passage 45, said valve 43 being closed at the ends and 110

forming a passage between ports in the flow of oil to the feed well 6 in the feeding process.

The nipple 49 is screwed into the passage

5 47 and the pipe 38 secured in said nipple 49, thereby connecting the feed well 7 to the feed well 6.

The nipple 50 is screwed into the passage 10 45 and this nipple is connected by the pipe 51 to the tank 52 thus completing a feed connection through from the oil tank 52 to the feed well 6 through the pipes and cylinder valve being controlled by the floats in the feed wells.

15 The stem 20 is screwed into the cylinder valve 32 and operated in a suitable slot in the wall of the valve chamber and the stem 22 is screwed into the cylinder valve 43 and operates in a suitable slot in the wall of 20 the valve chamber.

It will thus be seen that both cylinder valves are rotated by the rise and fall of the floats and in the operation of the feeding device the oil in the engine base 1 is 25 maintained at the same level as the predetermined highest level in one or other of the feed wells 6 or 7 or both as the case may be according to the road that the motor vehicle is traveling on.

30 The variation of the road surface does not in any way affect the efficiency of this device, as in going up hill one feed well will maintain the oil level in the base and in going down hill the other feed well will 35 maintain the level, while on the level road both wells will maintain the level.

There is always a free passage from one well to the other through the engine base and a controlled passage through the cylinder valves, consequently if going up hill 40 the feed well 6 is up then its float is down, but there is no feed because the float in the feed well 7 is up cutting the tank off. If going down hill and the feed well 7 is up then the tank is connected, but the float in well 6 is up and cuts off the feed, there, however no matter which well is up, should the level fall below a mean level sufficient for lubrication, then the tank will be connected to 45 the feed well 6 through the cylinder valve in the feed well 7 and the oil will continue to flow in until the proper level is reached and on the level ground the predetermined quantity or maximum will again flow in 55 through the same connection.

What I claim is:

1. In an engine base oil feeder, a feed tank, an engine base and a plurality of oil wells connected by a ~~free passage~~ through 60 said engine base and by a valve controlled passage fed from said tank.

2. In an engine base oil feeder, a feed tank, an engine base and a plurality of oil wells adapted to be rigidly secured at front 65 and rear of said base and connected to the

under side of said base from their lower ends, a pipe connection from said tank to an oil well, valves in said wells and pipe connections from valve to valve.

3. In an engine base oil feeder, a feed 70 tank, an engine base having a bottom oil inlet, pipe connections from said inlet, a front feed well and a rear feed well joined by said connections and rigidly secured to the base and having covers with vent orifices and cylindrical valve chambers, cylinder valves in said chambers, one of said valves having a port leading into the well and a port leading through the cover and connected to the other well and the other 75 valve forming a by-pass in connections from the tank to the first well and floats in said wells operatively connected to said valves.

4. In an engine base oil feeder, a feed 80 tank, an engine base having a bottom oil inlet, pipe connections from said inlet, a front feed well and a rear feed well joined by said connections and rigidly secured to the base and having covers carrying curved vent pipes and inner bosses bored to form 85 cylindrical valve chambers with inlet and outlet ports through the walls thereof, cylinder valves in said chambers, one of said valves having a port leading into the well and a port leading through the cover and connected to the other well and the other valve forming a by-pass in connections from 90 the tank to the first well, and floats in said wells operatively connected to said valves.

5. In an engine base oil feeder, a feed 95 tank, an engine base having a bottom oil inlet, pipe connections from said inlet, a front feed well and a rear feed well joined by said connections and rigidly secured to the base and having covers, one of said covers having an inner boss bored to form a cylindrical valve chamber with an outlet port leading to the interior of the wall and an inlet port and passage through boss and cover and the other cover having an inner boss bored to form a cylindrical valve chamber with parallel ports and passages through boss and cover, cylinder valves in said chambers, one of said valves having a port leading into the well and a port leading through the cover and connected to the other well and the other valve forming a by-pass in connections from the tank to the first well, and floats in said wells operatively connected to said valves.

6. In an engine base oil feeder, a feed 100 tank, an engine base having a bottom oil inlet, pipe connections from said inlet, a front feed well and a rear feed well joined by said connections and rigidly secured to the base and having covers with vent orifices and 105 cylindrical valve chambers, cylinder valves in said chambers, one of said valves having a port leading into the well and a port leading through the cover and connected to the other well and the other valve forming a by-pass in connections from the tank to the first well, and floats in said wells operatively connected to said valves.

110 115 120 125 130

other well and the other valve forming a by-pass in connections from the tank to the first well, and floats, each having a central post orifice and mounted on post guides 5 from the bottom of each well.

7. In an engine base oil feeder, a feed tank, an engine base having a bottom oil inlet, pipe connections from said inlet, a front feed well and a rear feed well joined by 10 said connections and rigidly secured to the base and having covers with vent orifices and cylindrical valve chambers, cylinder

valves in said chambers, one of said valves having a port leading into the well and a port leading through the cover and connected to the other well and the other valve forming a by-pass in connections from the tank to the first well, and floats having central stems screwed thereinto and adjustable and pivotally secured to valve stems 15 20 screwed into the cylinder valves.

Signed at Montreal, Canada, this 19th day of April, 1923.

LIONEL TREMBLAY.
